UNITED STATES PATENT OFFICE.

PETER A. PETERSON, OF OMAHA, NEBRASKA.

DUMP-WAGON.

1,392,445.

Specification of Letters Patent.

Patented Oct. 4, 1921.

Application filed June 24, 1920. Serial No. 391,474.

To all whom it may concern:

Be it known that I, PETER A. PETERSON, a citizen of the United States, residing at Omaha, in the county of Douglas and State 5 of Nebraska, have invented certain new and useful Improvements in a Dump-Wagon, of which the following is a specification.

This invention relates to an improvement in dump wagons, and has for its object to 10 provide such a construction that stresses occasioned by heavy loads will be adequately sustained, and that the doors may be under convenient control of an operator who may unload or dump the load at one side of the 15 vehicle before dumping at the other side is effected, or may dump the entire load by one operation. Other objects of the invention will be mentioned hereinafter.

In the accompanying drawing Figure 1 is 20 a plan view of a dump wagon embodying my invention. Fig. 2 is a side view of the same, the wheels at one side of the vehicle being removed. Fig. 3 is a view of the dump wagon in longitudinal section on line 25 3—3 of Fig. 1, the doors being swung downwardly and the tongue being omitted. Fig. 4 is a transverse section on line 4—4 of Fig. 1, one of the doors being swung downwardly. Fig. 5 is a view of the front end of the 30 dump wagon. Fig. 6 is a sectional detail showing a bushing for the bearings of a clutch. Fig. 7 is an enlarged detail to clearly show means to rotate a pair of miter gear-wheels for elevating the doors.

35 Referring now to the drawing for a more particular description, I provide a channel-iron 1 disposed at the medial line of the vehicle, bent to an irregular form to engage the front bolsters 2 and the rear axle 3, and 40 to provide a support for the respective front and rear ends 4 and 5 of the body of the vehicle, suitable upright partitions 6 being provided to which are secured the respective sides 7 and 8, between said upright partitions being provided the conventional recess 45 9 (Fig. 2) to permit swinging movements of the front axle 10 when "turning about."

According to the present construction the vehicle body is not provided with a bottom 50 and is not obstructed except by the bolster, the axle, partitions 6, and the channel iron 1 above mentioned, and the doors are arranged in pairs to swing downwardly from the channel iron from hinges 11, the pairs 55 of doors at the respective sides of the rear

axle as best shown at Figs. 2 and 3, being indicated at 12 and 13, the pair of doors between the partitions 6 being indicated at 14, and the pairs of doors at the respective sides of the front bolster being indicated at 15 and 16.

In order that the doors may be moved to a horizontal or closed position and may be there maintained for sustaining the weight of the load, and that they may be permitted to swing downwardly for dumping, I provide certain mechanism consisting in part of a pair of horizontal shafts 17 having bearings in brackets 18 which are secured to the sides of the vehicle body, chains 19 being secured to said shafts and adapted to be wound thereon, said chains also being secured to the outer ends of the doors; and it will be understood that a revolute movement of these shafts is depended upon for 70 elevating the doors to a closed position, and that, for the operation of dumping, these shafts are permitted to rotate.

Means now to be explained are provided for a control of the movements of shafts 17, 80 said means for the most part being mounted upon the front end of the vehicle body. As best shown in Fig. 7, I provide a pair of stub shafts 20 and 20', having bearings in a sleeve 21, each of said shafts being provided 85 at its outer end with a miter gear wheel 22, and, for causing rotary reciprocation of the sleeve, it is provided with an operating-lever 23.

At *a* and *b* are indicated a pair of clutches 90 which are slidably mounted upon the sleeve near the ends thereof, each being provided with a slot *c* for receiving a lug or projection *d* which is provided for the sleeve; and it will be understood that when the toothed 95 clutches are in engagement with the clutch-members or toothed hubs *e* of the wheels 22 an operator, by causing a swinging movement of the lever 23 forwardly, will cause a rotatable movement of the gear-wheels 22. 100 Bushings 35 are preferably employed for bearings of the clutches *a* and *b*.

Means are provided for moving each clutch into engagement with the hub of a wheel 22, and for causing its disengagement, 105 said means consisting of a pair of levers 24 and 25 mounted upon and adapted to swing from a fulcrum or pin *e*, each lever being provided with a pull-and-push rod *f*, which is connected with a clutch, the lever 24 pref- 110

erably being pivotally mounted between its ends as best shown in Fig. 3, so that its rod *f* may be connected at its lower end, to thereby cause simultaneous outward or inward movements of the clutches when both levers 24 and 25 are moved in one direction, this being of great convenience during operation; and it will be noted that the clutches may be moved independently of each other, 10 and that one clutch may be disengaged from a gear wheel 22 while the other clutch remains in engagement with the opposite gear wheel.

Since the gear wheels 22 of shafts 20 and 15 20' are constantly in engagement with the gear wheels 26 of the side-shafts 17, a rotation in one direction of the stub-shafts 20 and 20' will cause rotation of said shafts 17 to cause the chains to become wound thereon 20 for elevating and closing the doors, the clutches *a* and *b* being then in engagement with the wheels 22, a downward swinging movement of the doors during this operation being prevented by means of ratchet-wheels 27 and pawls 28 best shown in Figs. 1 25 and 2, the ratchet wheels being rigidly mounted on shafts 17 and the pawls being pivotally mounted between their ends in arms 29, the latter being pivotally mounted 30 upon the sides of the vehicle box, bull-and-push rods 30 being employed and extending forwardly of the vehicle, their rear ends being pivotally connected with the arms 29, and the front end of each rod 30 being pivotally connected with an arm *g* of a crank-shaft 31, said shafts 31 having bearings in 35 brackets 32 which are mounted upon the front end of the box, and each of said shafts 31 being provided with a pedal-arm 33.

40 As thus described, an operator may cause an arm 33 to swing forwardly to cause a forward swinging movement of an arm 29 for causing disengagement of a pawl 28 from a ratchet-wheel, this movement being subject 45 to the resistance of a spring 34 (Fig. 2).

Numerals 36 indicate brake-shoes adapted to be pressed against the rear wheels by use 50 of a treadle-arm 37, which is adapted to rotate a horizontal crank shaft 38, which is mounted upon and at the front of the box, 55 said crank-shaft 38 being provided with a push-bar 39 which extends rearwardly for a connection with the upper end of a rock-lever 40 which is rigidly mounted between its ends upon a cross-bar or shaft 41 which is disposed below and is supported by the rear axle 3, and is provided at one of its ends with a crank-arm 40'.

Numerals 42 (Fig. 2) indicates a connecting-rod at one side of the vehicle, said rod having its front end secured to the brake-shoe, its rear end being pivotally connected with the lower end of the rock-lever 40, and it will be understood that the rod 42 at the

opposite side of the vehicle and shown in 65 Fig. 1 is for the same purpose, and connects the lower end of the rock-lever 40' with a brake-shoe.

Having fully described construction, operation will be readily understood. The 70 doors may be swung upwardly by use of the hand lever 23 to cause reciprocatory rotation of the sleeve 21, the clutches *a* and *b* being in engagement with the wheels 22, the chains 19 thereby being wound upon the 75 shaft 17.

When it is desired to dump a load, the clutches *a* and *b* may be moved toward each other by use of the levers 24 and 25 to release the clutches from the gear wheels 22, 80 and by moving the treadle arms 33 the pawls 28 will be disengaged from the ratchet-wheels 27, the shafts 17 thereby being free to rotate to permit the doors to swing downwardly to open position. 85

It will be noted that the treadle-arms 33 are disposed closely adjacent to each other so that operation will be convenient for swinging them coincidently when dumping 90 a load.

Among some of the advantages to be derived by use of the invention it may be stated that a containing space is provided for a load which is greater than ordinary, dumping being provided for the entire length of the box; also by use of the channel-iron, and its form and arrangement, stresses directed to the box and doors will be adequately sustained. Also the construction permits dumping at either side of the vehicle, for the reason that the shafts 17 may rotate independently of each other, this frequently being of great advantage when dumping the loads to fill pockets or depressions, or when discharging a load upon inclines in instances where 105 it is desired that the greater part of the load will move toward the "near" or "off" side of the vehicle.

I claim:

1. In combination with a vehicle body 110 having openings in its bottom and having doors hingeably mounted thereon adjacent to said openings, a pair of operating-shafts mounted on the sides of the vehicle body, each being provided with a gear wheel, flexible strands connecting the operating shafts with the doors and adapted to be moved by a revoluble movement of the operating-shafts for moving the doors into closed relation with said openings, a sleeve, a pair of tubular clutch-members each circumscribing the sleeve and having bearings in the vehicle-body, a pair of gear-wheels each being provided with a clutch-member and rigidly mounted on a stub-shaft in engagement with 115 a gear-wheel of an operating-shaft, means for moving the clutch-members on the sleeve into engagement with the clutch-members of 120 125

the gear-wheels of the stub-shafts, and means to rotate the sleeve for rotating the operating-shafts.

2. In combination with a vehicle body having openings in its bottom and having doors adjacent to said openings, a pair of operating-shafts at the sides of said body, each being provided with a ratchet-wheel and a gear-wheel, flexible members connecting the operating shafts with the doors and adapted to be moved by the revoluble movement of the operating-shafts for moving the doors into closed relation with said openings, a sleeve, a pair of tubular clutch-members each circumscribing the sleeve and having bearings in the vehicle body, a pair of gear-wheels each being provided with a clutch-member and rigidly mounted on a stub-shaft in engagement with a gear-wheel of an operating-shaft, means for moving the clutch-members on the sleeve into engagement with the clutch-members of the gear-wheels of the stub-shafts, means to rotate the sleeve for rotating the operating-shafts, and a pair of pawls on the vehicle-body normally engaging the ratchet-wheels of the operating-shafts.

3. In combination with a vehicle body

having openings in its bottom and having doors thereon adjacent to said openings, a sleeve, a pair of clutch-members circumscribing the sleeve, a pair of stub-shafts having bearings in the sleeve, a pair of gear-wheels each being rigidly mounted on a stub-shaft and provided with a clutch-member, a pair of operating-shafts having bearings at the sides of the vehicle body, each being provided with a ratchet-wheel and having a gear-wheel constantly engaging a gear-wheel of a stub-shaft, flexible members connecting the operating-shafts with the doors and movable by actuation of said operating-shafts for moving the doors into closed relation with said openings, a pair of hand-levers each being movable for moving a clutch-member of the sleeve into engagement with the clutch-member of the gear-wheel of a stub-shaft, said sleeve being revoluble for rotating the gear-wheels of the stub-shafts to actuate the operating-shafts.

In testimony whereof I have affixed my signature in presence of two witnesses.

PETER A. PETERSON.
